UNITED STATES PATENT OFFICE

2,683,497

COOLING DUCT ARRANGEMENT FOR
AIR-COOLED MOTORSHermann Klaue, Überlingen (Bodensee),
Germany

Application March 26, 1951, Serial No. 217,606

Claims priority, application Germany
March 27, 1950

2 Claims. (Cl. 180—54)

1

The invention relates to the problem to use air-cooled motors in small motor cars without a blast-engine for the purpose to spare expenses. The cooling of such motors employed up to now includes the danger that the cylinders are not sufficiently cooled. It has been stated by tests that if an approximately streamline shaped car body moves on a track way which is at a standstill a strong overpressure results at the front side of the car and a strong vacuum at the first third of the lower side. The invention described hereafter uses this knowledge for the purpose to get a best possible cooling effect.

The invention starts from an arrangement of the motor having its crank shaft arranged across the driving direction of the motor car. The invention consists in that the motor cylinders, which are suspended, project into a cooling channel extending rearward from the front side of the car to the lower side of the car body; the upper delimitation of which is formed by the crank casting, the gearing and the drive or a guide sheet respectively.

The drawing shows an embodiment of the invention by way of example. The figure illustrates a longitudinal section through the air-cooling channel provided in the front portion of the motor car.

The reference numeral 1 designates a leading wheel and 2 the car body provided with a cooling channel 10. At the front side of the car body an air entrance 3 and on the lower side of the car body an exit opening 4 is provided. The cylinders 5 of the motor are suspended within the said cooling channel. The crank casing 6, the gearing 7 and the drive 8 are arranged across the driving direction of the motor car outside of the cooling channel 10 proper. The cooling air is guided by a guide sheet 9 separating the cooling channel 10 from the other motor space. The lower side of the cooling channel is limited by the guide sheet 11.

As a strong overpressure exists at the front side of the running car and a strong vacuum at the first third of the lower side the cooling air is 45 sucked in through the front opening 3 of the cooling channel 10. The air stream cools the

motor cylinders 5 so well that a cooling by a ventilator is superfluous. The abolition of the ventilator drive discharges the motor from this work.

Having thus particularly described the nature 5 of my said invention and the manner in which the same is to be performed, what I wish to have covered by Letters Patent is:

1. In a cooling device for motor cars an air duct sloping in a downward direction from the front 10 of the car to the front portion of its underside in combination an inclined crank case containing a crank shaft and gears journaled therein having their axes extending at a right angle to the traveling direction of the car, said crank case extending above and in the sloping direction of said air duct and motor cylinders suspended from said inclined crank case and projecting into said air duct.

2. In a cooling device for motor cars an air duct sloping in a downward direction from the front 20 of the car to its underside in combination an inclined crank case containing a crank shaft and gear journaled therein having their axes extending at a right angle to the traveling direction of the car, said crank case extending above 25 and in the sloping direction of said air duct and motor cylinders suspended from said inclined crank case and projecting into said air duct and an upper and a lower guide sheet limiting the 30 upper and the lower side of said air duct.
